UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A LAMP-FOUNT HOLDER.

SPECIFICATION forming part of Design No. 20,865, dated June 30, 1891.

Application filed June 1, 1891. Serial No. 394,761. Term of patent 14 years.

To all whom it may concern:

Be it known that I, ALBERT PATITZ, of Meriden, in the county of New Haven and State of Connecticut, have invented a new Design 5 for Lamp-Fount Holders, (Case B;) and I do hereby declare the following, when taken in connection with accompanying drawing, and the letters of reference marked thereon, to be a full, clear, and exact description of the same, 10 and which said drawing constitutes part of this specification and represents a perspective view of the holder.

This invention relates to a design for that part of a standard lamp in which the removable fount is supported, called the "fount-holder." It is of spherical shape in outline or circular in transverse section and expands by an outward curve from the lower side upward, thence contracting by a similar curve

to the top. On the side of the fount is the 20 representation of a medallion-head surrounded by the representation of a frame and that surrounded by tracery of floriated scroll-work inclosed by a band forming a panel on the side of the holder, as shown in the accompanying 25 illustration.

I claim—

The design for a lamp-fount holder, as herein described, and shown in the accompanying illustration.

In testimony whereof I have signed this specification in the presence of two subscribing witnesses.

ALBERT PATITZ.

Witnesses:
